CYCLE PEDAL TREAD BLOCK

Hugh T. Greenlee, Gates Mills, Ohio, assignor to Ashtabula Bow Socket Company, Ashtabula, Ohio, a corporation of Ohio

Filed Oct. 18, 1968, Ser. No. 14,072

Term of patent 14 years

Int. Cl. D12—14

U.S. Cl. D90—14

FIG. 1

FIG. 2

FIG. 3

FIG. 4

FIG. 5

FIG. 6

FIG. 1 is a top plan view showing my new design of a cycle pedal tread block;

FIG. 2 is a side elevational view of the tread block of FIG. 1;

FIG. 3 is an end elevational view of the tread block of FIG. 1;

FIG. 4 is a top plan view showing a modification of my new design of a cycle pedal tread block;

FIG. 5 is a side elevational view of the tread block of FIG. 4;

FIG. 6 is an end elevational view of the tread block of FIG. 4.

The dotted line showings in the drawings are for illustrative purposes only.

I claim:

The ornamental design for a cycle pedal tread block, as shown and described.
